UNITED STATES PATENT OFFICE

LEWIS C. NORTON, OF ALTADENA, CALIFORNIA, ASSIGNOR TO NORTON-LASIER CO., OF CHICAGO, ILLINOIS, A CORPORATION OF ILLINOIS

DOORCHECK, FLOOR TYPE

Application filed November 21, 1927. Serial No. 234,783.

This invention relates to door checks and particularly the type of door checks which are placed in the floor beneath the door or in the sash above the door out of sight, as distinguished from the type mounted in view on the door or the door sill.

The invention contemplates both single acting and double acting door checks, the single acting checks being adapted for operation on doors which swing in only one direction and close against the door jamb, whereas the double acting checks are constructed for use with doors swinging in both directions from the closed position.

15 The single acting door checks contemplated in this invention are so constructed that by a mere rearrangement of the parts constituting the check, the check is adapted for installation on either right or left-hand doors.

20 This invention further contemplates the type of door check which operates to close the door by spring action and to check the closing action by means of a fluid checking device, all of the parts being so connected together and with the door as to give the desired closing and checking effect.

Accordingly, one of the objects of this invention is to provide an improved and practical door check which is highly efficient in 30 operation, comparatively simple in structure, practical and cheap to manufacture, easy to install and one which imparts to the door an improved movement in the closing and checking operation.

35 Another object of this invention is to provide a door check which may be applied to a door of either the single or double acting type after the door has been mounted on its hinges and one in which part of the connecting 40 mechanism between the door check and the door is mounted on the door and part is mounted on the door check, which parts may be readily brought together and connected to complete the connecting mechanism between 45 the two.

Another object of this invention is to provide a door check, the spring resistance of which is greater at the latch, and which will offer less resistance to the opening of the door 50 as the door opens.

Another object of this invention is to provide in the single acting type a check which is readily convertible, by mere reversibility of parts, to adapt the check for installation on either a right or left-hand door.

55 Another object of this invention is to provide a door check which employs a main operating spindle which is off center line of the hinges of the door when installed, and to provide connecting means therefor, which is located for the greatest part beneath the door in all positions of operation so that the connecting means is substantially concealed and out of the way at all times.

Another object of this invention is to provide a door check in which the spring tension 65 may be more readily adjusted than in devices heretofore devised.

Another object of this invention is to provide a hold-open feature whereby the check 70 operates to maintain the door in a predetermined open position, and one where the hold-open operation can be eliminated by merely adjusting the parts.

A further object of this invention is to 75 provide a holdopen feature which is capable of holding the door open in any one of a plurality of selected open positions.

It is a further object of this invention to provide a back check feature whereby the 80 door check offers resistance to a further opening movement after the door has been opened a predetermined amount.

A further object of this invention is to provide a door check, the spring force for closing the door of which is adjustable without changing the tension of the spring directly, but by merely shifting the door check bodily in its installed position relative to the center line of the door.

90 Another object of this invention is to provide a door check, the fluid checking device of which has a new and improved checking action, both in the closing action and in the back check action.

95 A further object of this invention is to provide a door check which is mounted in a water-tight casing and may be readily installed in either a cement floor or wooden floor.

A further object of this invention is to provide a door check incorporating in its structure anti-friction bearings, which greatly reduce the internal friction of the device and makes for a smoother and easier operation.

A further object of this device is to provide both single and double acting checks in which some of the parts of one type are interchangeable with the corresponding parts of 10 the other type, thereby reducing manufacturing costs.

A further object of this invention is to provide a check, the fluid checking device of which is readily adjusted and is capable of 15 more flexible adjustment and operation than in devices heretofore known.

A further object of my invention is to provide a check of the double acting type by which the door is readily centered by adjusting 20 the check so as to bring the door to the center line of the door sill when in closed position.

These and other objects are accomplished by means of the arrangement disclosed in the 25 accompanying sheets of drawings, in which—

Figure 1 is a fragmentary perspective view of the single acting type of check, constructed in accordance with this invention, mounted on a left-hand door.

30 Figure 2 is a plan view of the check proper, with the top removed disclosing the internal construction.

Figure 3 is a cross sectional elevational view of the single acting check shown in Figure 2 and taken on the line 3—3 of Figure 2 and looking in the direction of the arrows.

Figure 4 is an end elevational view in section taken on the line 4—4 of Figure 3 and looking in the direction of the arrows.

40 Figure 5 is a cross sectional plan view of the fluid checking device of the single acting type.

Figure 6 is a perspective view of the double acting check in its installed position.

45 Figure 7 is a plan view of the double acting check with the top removed disclosing the internal construction.

Figure 8 is a cross sectional elevation taken on the line 8—8 of Figure 7 looking in the direction of the arrows.

50 Figure 9 is a cross sectional elevation taken on the line 9—9 of Figure 7 and looking in the direction of the arrows.

Figure 10 is an enlarged sectional elevation of the holding device employed in the double acting check.

55 Figures 11 and 12 are respectively the upper and lower hinge constructions for the double acting door, both views being cross 60 sectional side elevations.

Figure 13 is a perspective view of the two-part connecting link between the check and door; and

65 Figure 14 is an enlarged cross sectional view through the slide guide and connecting

arm for connecting the door and door check.

The various novel features of the invention will be apparent from the following description and will be particularly pointed out in the appended claims.

Referring to the drawings, and particularly to Figures 1 to 5, inclusive, and Figures 13 and 14, the single acting check will now be described.

It will be noted as shown in Figure 1 that 75 the preferred installation of the door check 20 is below the door at substantially the center line of the door sill. The door 21 of the customary type, mounted on the usual hinges 22 has provided in the bottom edge thereof 80 a slide guide 23 having inwardly bent flanges 24 at its bottom to provide a track 25 therein for accommodating the slide block 26.

By referring to Figures 13 and 14 it will be noted that the block is perforated as at 85 27 to accommodate the pin 28, flanged at its top 29 to prevent removal thereof, the pin 28 being made as an integral, or otherwise rigidly attached, part of the female portion 30 of the connecting arm. The side of the female 90 member 30 is provided with a screw opening 31 to accommodate the set screw 32. The main portion of the connecting arm 33 is provided with an apertured head 34 adapted to be secured with a non-turning fit to the 95 main operating spindle 35 of the door check and secured as by means of the screw 36. The outer end of the connecting arm 33 has a reduced end 37 constituting the male member 100 of the connection which is received in the female member and secured therein as by means of the set screw 32, as shown in Figure 14.

Attention at this point is directed to the fact that the parts 30 and 33 constituting the 105 connecting arm are comparatively flat and in many installations where the bottom of the door is slightly spaced above the floor or door sill, the arm may be conveniently placed therebetween without removing a portion of the door to accommodate the arm, but in installations where the door is too close to the floor or door sill, the door will be cut away to form a slight clearance as at 38, shown in Figure 1. The slide block 26 may be of the friction type, but on very heavy doors where the friction is excessive the side edges of the block may be recessed with ball bearings placed therein so that an anti-friction slide connection is provided. The balls may contact in such a case the plane vertical sides of the guide or run in grooves provided therein as desired. In other installations a single roller mounted on the pin 28 may be provided with sufficient clearance between the opposite 115 sides of the guide to permit rolling thereof without binding.

Referring now to Figures 2 to 5, inclusive, it will be noted that the single acting check embodies a main casing 39 provided with a 130

top plate 40 suitably secured thereto, which top is provided with an opening 41 at one end and a circular upstanding flange 42 formed from the top around the periphery of the opening.

As shown in Figure 3, when the check is to be mounted in a concrete floor an additional metallic casing 43 is provided adapted to receive the main casing 39, this casing being mounted in the concrete floor at the time the concrete is poured, in a manner to constitute a receptacle in which the door check is placed. Around the upper edge of the casing 43, packing material 44 is provided whereby a water-tight seal is effected to prevent moisture and dirt from entering the interior of the check. In all installations it is preferable to provide a finished cover plate 45 to improve the appearance thereof. The operating arm 33 is provided on its under surface with an annular groove 46 in which is placed suitable packing 47 in a manner to cooperate with the upstanding flange 42 on the cover to complete the seal for the checking device, this construction preventing water, dirt and other detrimental material from entering the interior of the casing through the spindle opening.

Positioned at one end and longitudinally disposed in the casing is the fluid checking device designated generally as 48, the particular construction of which will be herein-after described. The fluid checking device is attached to the bottom of the casing by means of screws 49, which penetrate and bind the flange 50 made integral with the fluid checking device with the bottom wall of the casing. The fluid checking device is positioned as shown in Figure 2, relative to the casing, for door checks of one hand, but this invention contemplates bodily reversing the door checking device in the casing for doors of the opposite hand, it merely being necessary in such a case to reverse the position of the fluid checking device and fasten the screws 49 in holes which will be provided at the opposite side of the center line of the casing in corresponding positions. The fluid checking device constitutes a complete unit which may be assembled outside the casing and is the part of the device in which the main operating spindle 35 is mounted.

At the opposite end of the casing on the center line of the bottom wall an upstanding drilled boss 51 is provided, screw threaded in a manner to receive the threaded reduced end 52 of the spring spindle 53. Positioned between the shoulder formed by the reduced end of the spindle and the boss is a supporting plate 54 on which the spring and hub element of the spring assembly rests. The plate 54 and the spindle 53 are rigid with the casing. The hub 55 is mounted on the spindle and is provided at its top with a flange 56 which overlies the spring coils and has pro-

vided on its upper surface a plurality of substantially triangular lugs 57. The bottom end of the hub is formed with the bearing surface 58 adapted to take the radial load by contact with the lower portion of the spindle. The upper portion of the hub is mounted to turn on the upper portion of the spindle by means of an anti-friction bearing comprising the outer race ring 59, the inner race ring 60 and the ball bearing 61. The hub is provided along its length at one side with a groove 62 in which one end 63 of the flat coil spring 64 is secured, the outer end of the coil spring being provided with a hooked portion 65, which is anchored to one of the lugs 66 or 67 provided as in an integral or otherwise rigidly fixed part of the casing 39.

A flexible element such as the chain 68 is positioned about the upper portion of the hub 55, resting on the flange 56 and is fixed thereto by means of the hook 69 at the end thereof, engaging selectively one of the plurality of lugs 57 provided on the upper surface of the hub. The opposite end of the chain 68 is provided with an elongated link 70 which is connected by means of the pin 71 to the hooked portion 72 of the hub 73 provided on the upper end of the main spindle 35 and fixed to turn therewith.

Attention is directed to the fact that the hub 73 throughout a greater portion of its diameter, is of a reduced size as at 74, the reduction of which is considerably less than the length from the center of the spindle to the point of attachment of the pin 71 to the hook 72, and that due to this fact the movement of the spring through the chain by the turning of the main spindle 35 has a constantly varying effect which operates, for a constant angular velocity of the main spindle, to impart a negatively accelerated velocity to the spring hub.

Referring now particularly to Figures 3 to 5, inclusive, it will be noted that the fluid checking device comprises a cylindrical casing 75 having an upstanding cylindrical extension 76 on the top thereof, the ends of the cylinder 75 being closed by means of the screw threaded plugs 77. The spindle 35 is mounted to one side of the center line of the cylinder 75 by means of the reduced end 78 of the spindle being mounted in the bearing socket 79 in the casing. The lower portion of the spindle is constructed to form a gear 80, which meshes with the rack 81 provided on the double headed piston 82 positioned to slide in the cylinder 75. The upper cylindrical portion 76 is internally threaded at 83 for receiving the closing cap 84, which is flanged in a manner to overlie the upper edge of the cylindrical portion 76. The closing cap is provided in its upper surface with a circular recess 85 in which is mounted the anti-friction bearing comprising the outer race ring 86, the inner race ring 87 and the

lower bearing 88. This bearing is adapted to support the greater portion of the radial load imparted to the spindle 35 during operation. The closing cap 84 is further recessed below the bearing as at 89, the recess being partially threaded as at 90, in a manner to accommodate the packing 91 and the gland ring 92 for forming a liquid seal for the spindle. Attention is directed to the fact 5 that the closing cap extends downwardly, acting somewhat in the capacity of a journal bearing for the lower portion of the spindle and in this portion is provided an internal groove 93 which is connected with the interior of the cylinder 75 by means of the angular radial ports 94 in a manner to form an oil seal which, together with the packing, prevents the escape of the fluid from the checking device. Each head of the piston is provided 10 with an opening 95 therethrough, providing a seat at its inner end to cooperate with the ball 96 held against displacement by the pin 97 to form a one-way check valve. The valve operates to pass fluid therethrough 15 from the central portion of the checking device to the end chamber, when a particular piston moves away from that end. The valve passes no fluid, however, when that particular piston is moving in the opposite direction or approaching the cylinder end. 20

As shown in Figure 5, the cylindrical casting 75 has an enlarged rib 98 on one side thereof, which is drilled to form the passage-way 99 and the two ports 100 and 101. Screw 25 threaded through the rib in a manner to adjust the opening in the passage 99 are screws 102 and 103, the screw 102 being positioned to effect the size of the passage-way 99 between the location of the ports 100 and 101 and the screw 103 being positioned between the ports 101 and the open end 104 of the passage 99. The heads of the screws are constructed and located in a manner to render them easily adjusted. 30

45 The passage and port construction above described is duplicated at both ends of the piston and the single description will suffice for both. On the cylindrical surface of the piston heads a V-shaped groove 105 is provided, so located and constructed that the large end extends toward the end of the cylinder and to cause the groove during the movement of the piston to pass over the ports 101 and 100. This is for the purpose of effecting a new and desirable checking action 50 which will be hereinafter described. 55

60 By referring to Figure 2, it will be noted that this invention embodies a hold-open feature which in the present form consists of a segmental enlargement 106 on the hub 73, the segmental enlargement on its cylindrical surface being provided with a plurality of radial openings 107 which may be screw threaded as shown, or provided with smooth 65 faces, but in either case constructed to selec-

tively receive by a snug fit the pin 108. The shank of the pin extends into the opening and is provided with a head 109 preferably with an oval or egg-shaped curved outer surface. Mounted on the side of the casing 70 39 as by means of the screw 110 is an elongated leaf spring 111 having its unattached end 112 in sliding bearing relation against the side wall of the housing. Positioned substantially centrally of the leaf spring is the opening 113 having its edge adjacent the fluid checking device slightly beveled. The opening 113 cooperates with the head 109 of the pin carried by the hub to hold the parts 75 against rotation and as a result holds the door in open position. It is to be understood that only one pin is employed for a particular adjustment, the pin being selectively located in any one of the plurality of openings 107 as desired so that the door will be held after it has been opened a predetermined extent. The particular hole 107 which is selected for locating the pin 108 is determined by the amount of opening at which it is desired to hold the door. 80

Attention is directed to the fact that the holding spring is relatively long and therefore quite flexible without necessitating great bending thereof. This makes for long life and in practice this type of spring will serve 95 the full life of the checking device. 90

Referring now to the double acting type of check disclosed in Figures 6 to 11, inclusive, it will be noted that the manner of connecting the door check to the door is substantially similar to that disclosed in connection with the single acting check. Similar reference characters are employed in the drawings. 100

By referring to Figure 6 it will be noted that a separate hinge is provided adapted to overlie a portion of the check, but in a manner to provide separate centers for the main spindle of the check and the door hinge. 105

It is to be understood in mounting either the single or double acting type that great flexibility is allowed through the type of connection provided in locating the door check, both in a direction from side to side of the door opening and on either side of the center line of the door. The preferable way of mounting the double acting check is in the manner shown, the location of the check under the door hinge permitting the two centers to be located quite close in a manner to maintain the connecting arm in all positions out of the way. The lower hinge 114 with a double acting door preferably comprises an L-shaped plate adapted to be secured by means of screws 115 to the door sill and leaving the horizontal arm of the bracket unsecured and adapted to overlie a portion of the door check. On the upper surface of the horizontal arm an annular upstanding flange 116 is provided in which is mounted 110 115 120 125 130

the combined radial and thrust anti-friction bearing 117. Positioned on the bottom face of the door is a plate 118, having downwardly projecting boss 119 secured by means of the screw 120 and in a manner to position the boss for support in the inner race ring of the antifriction bearing. The slide, slide block and connecting arm are constructed similar to the device described in connection with the single acting check. The main spindle of the double acting check is adapted to rotate from the neutral or closed door position in both directions and to function similarly in either direction of swing.

Referring now particularly to Figure 7, it will be noted that the internal construction of the double acting check embodies a fluid checking device 121, which will be hereinafter more fully described, and two separate spring devices 122 and 123, one only of which operates at a time, one acting to close the door after it has been opened in one direction from the neutral position and the other to close the door after it has been opened in the opposite direction from the neutral position. The spring mechanism 122 is mounted on a spindle 124 and the spring mechanism 123 is mounted on the spindle 125, both of the spindles being screwed to the bottom of the casing as shown in Figure 9 and in a manner similar to that described in connection with the single acting check. The structure of these spring units is exactly similar to those previously described and, therefore, it is considered that the same reference characters will serve and that a further description is unnecessary. It is only important to notice in this connection that the two springs are wound in opposite directions so that they will be adapted to close the door from the opposite open positions and that the ends of the springs are secured to lugs 126 integral with or otherwise rigidly secured to the casing. The casing in the double acting check is designated by the numeral 127. The double check also embodies flexible attaching elements such as the chains 128 and 129 for connecting the fluid checking device and the spring mechanism. The hooks 69' are of similar construction to those previously described. The opposite ends of the flexible elements are slightly modified in the double acting check in that the elongated links 130 are provided which carry pins 131 at their ends adapted to releasably engage the hooks 132 disposed in substantially opposite relationship on the hub 133. The pins 131 are formed with an enlarged head 134, as shown in Figure 9, which is located below the links, and are held in position with the pins by means of shoulders provided by the heads and the flattened end of the pin at the top. The heads 134 are provided on one face with a conical opening 135 so constructed and positioned as to cooperate with the conical end of the screws 136 which are mounted by a screw

threaded engagement through the lugs 137 made integral or otherwise rigidly attached to the upper surfaces of the fluid check casing. It is understood that the hub 133 is rigidly fixed to turn with the main fluid check 70 spindle 138 and that the arms 132 will swing in an arc around the axis of the spindle. The links 130 are so designed that the hooked portions 132 may swing away from the pins 131 and pass out between the links in a manner to 75 permit the ends of the flexible chain to remain in position anchored on the end of the screw bolt 136.

In this connection it will be understood that as the door swings in one direction from the 80 neutral position that one of the arms 132 will approach its spring device, whereas the opposite arm will swing away from the other spring device and that in this construction the arm swinging away will wind the spring 85 to which it is connected and the opposite arm will swing free of the pin 131, permitting the end link and chain to remain in position while the arm passes out between the links. On swinging back to neutral position the free 90 arm again comes into position where its hook engages the pin and a continued movement in that direction will cause the arm to remove the link from its seat on the screw 136 and to carry it forward in a manner to wind the 95 spring to which it is connected. This construction permits the springs to be operated one at a time, leaving the spring which is not employed to remain immobile during the operation of the other spring.

It will be readily appreciated that by adjusting the opposite screws 136 that the neutral position of the door will be determined and that there is provided by this construction a means for readily adjusting the door to the 105 center line of the door sill. The tension of the individual springs can be adjusted by winding the hubs and securing the hooks 69' to the lugs as desired.

The fluid checking device is provided with 110 flanges 139 at opposite sides of its base, through which the screws 140 are positioned for engagement with screw openings in the bottom wall of the casing for securing the fluid checking device in position. The fluid 115 checking device comprises a main cylinder 141 formed by the cylindrical wall 142 having an upstanding cylinder sleeve 143 for accommodating the anti-friction bearing 144. The main spindle 138 is positioned 120 through the anti-friction bearing in a manner for radial support and having its lower end bearing in a socket not shown in the drawings provided in the lower end of the cylindrical casing in a manner similar to 125 that shown in Figure 4 of the single acting check. The upper end of the cylinder is closed by means of a cap 145 screw threaded in the cylinder sleeve 143, which cap is recessed at 146 to receive the anti-friction 130

bearing, the lower end of the cap projecting downwardly as at 147 in a manner to accommodate the packing for forming the seal at 148. The opposite ends of the cylinder 141 are closed as by means of the end caps 149 and 150. Positioned in the cylinder is a double headed piston 151 provided with a double rack 152 adapted to cooperate with the mutilated gear 153 formed on the lower portion of the main spindle 138. The gear and rack are so constructed that for movement of the spindle in either direction from the neutral position the piston will be moved in the same direction towards the opposite end of the cylinder, the cylinder being initially installed relative to the gear so that in the neutral position the piston is located at its extreme position at one end of the cylinder. This end of the cylinder constitutes the checking end and an enlarged rib 154 is provided with the fluid passage 155 formed therein communicating with the end of the cylinder by means of the two ports 156 and 157. Adjustment screws 158 and 159 are provided in the passage 155 in a manner similar to that described in connection with the single acting check. The head of the piston at the checking end of the cylinder is provided with a ball check valve 160 constructed in a manner similar to the check valve described in the single acting check so that this piston head will pass fluid when moving in a direction away from the checking end of the cylinder. The opposite piston head is solid, but is provided with a V-shaped groove 161, with the large end of the groove extending toward the end of the cylinder. The V-shaped groove is adapted to cooperate with the groove 162 provided in the interior wall surface of the cylinder, the V-shaped groove in the piston head and the groove 162 in the cylinder wall forming means for establishing a back check feature for the door in either direction of movement from the center line, the groove in the cylinder wall serving to pass fluid when the piston is moving away from the checking end of the cylinder as when the door is opened, the groove terminating at a point slightly in advance of that where the cooperating piston head is located when it is desired to check the opening of the door, the final back checking action being produced gradually by means of the V groove in the piston head passing over the end of the groove 162 in a manner to diminish the fluid passage and ultimately to prevent the passage of fluid entirely. After the V groove has completely passed the groove 162 the fluid trapped between the solid piston head and the end of the cylinder checks the door against further opening movement. Attention is directed to the fact that the piston head at the checking end of the cylinder is also provided with a V groove 163 constructed similar to and adapted to

function in the same manner as the groove 105 in the single acting check.

The means for holding the door in open position in the double acting device comprises a spring pressed plunger 164, as shown in Figure 10, mounted at the center of the fluid checking cylinder, as shown in Figure 7. The plunger is adapted to slide in the lugs 165 and 166 made integral with or otherwise rigidly secured to the fluid checking device and is spring pressed upwardly by means of the spring 167. A flange 168 is provided at the base of the head of the plunger to prevent the plunger being displaced upwardly. The upper surface of the plunger head is mounted and is adapted to cooperate with the arms 132 which swing in a horizontal plane in a manner to engage behind the lug, the leading contacting edge being beveled as at 133 to aid in camming the plunger downwardly to permit the arms to pass. The single plunger serves for both the arms 132, which engage therewith to lock the door in open position in either direction of swing, depending upon which one of the arms 132 is swung inwardly.

Inasmuch as the maximum opening for single acting doors is substantially 90 degrees, the single holding device will serve for both arms, the parts being constructed to bring the arms in engagement with the plunger when the desired amount of opening has been effected.

By referring to Figure 11 it will be noted that the upper hinge of the double acting door comprises a frame or housing member 169 having cylindrical guides 170 and 170' thereon for receiving the plunger pin 171 and nut 174, respectively. The plunger pin is provided with a slot in its upper portion for pivotally receiving by means of the pivot 171, arm 172, which extends through the slot 173 in the cylindrical guide and is attached to the nut 174. The nut 174 is provided with a screw threaded opening for engaging the screw 175. The screw has a swivel fit by means of the counter sunk hole provided for the head and the over-lapping plate 177, whereby it is free to rotate but is held against axial displacement. The head of the screw 178 is presented to the opening in the plate 177 so that the head of the screw is readily accessible when the door is swung away from its closed position. The upper edge of the door is provided with a plate 179 secured by means of screws 180, and is provided with a cylindrical opening 181 adapted to receive and form a hinge with the depending end of the plunger 171.

It will be obvious from this construction that in order to remove the door it is merely necessary to swing the door an extent sufficient to expose the head of the screw and to turn the screw sufficiently to raise the plunger pin out of the socket 181, whereby

the upper end of the door is removed from its pivot and the lower end of the door may be lifted out of the anti-friction bearing socket.

- 5 In operation the single acting check as initially installed is constructed with the piston mounted in one end of the cylinder with the rack and gear in mesh when the operating arm 33 is in neutral position as when the door 10 is closed against the door jamb. The parts are so arranged for a door of a particular hand that when the door is opened the arm will be moved in a manner to move the piston to the opposite end of the cylinder, this 15 end being the non-checking end. The screws regulating the valve ports at the non-checking end will preferably be screwed entirely outwardly in a manner to offer no resistance to fluid flow, except in the case where a back 20 check is desired. When a back check is desired, it is preferable to leave the first port open so that the first opening movement of the door is uninfluenced and the last port is entirely shut off, whereby the trapped fluid 25 between the port 101 and the end of the cylinder is caused to pass through the groove 105 to give a gradually increasing checking action and finally offer complete resistance to further opening movement. When the 30 door is permitted to swing shut the closing of the door is caused by the tension of the spring which was wound up during the opening movement, and causes the piston of the fluid checking device to approach the checking 35 end of the cylinder or the righthand end as shown in Figure 3. At the checking end of the cylinder the two screws are adjusted to accomplish the checking speeds desired, the screw 103 determining the initial speed 40 and the screw 102 determining the latch speed. The lever arrangement between the parts is such that the piston travels up to and passes over the port 101 during the greater part of its swing and the further 45 movement of the piston is that which is effected when the door travels the last short distance in approaching the latch. The groove 105 permits an intermediate speed whereby the initial speed of the door is greatly diminished before the final latch speed 50 port 101 is brought into play. In the event a very slow closing movement at the latch is desired, port 101 can be shut off entirely by means of screwing the screw all the way 55 down, in which case the door will close with rapid movement by the escape of fluid through the port 101 with a gradually diminishing speed by means of the V groove 105, with a final extremely slow seating action 60 at the latch by means of leaking of fluid past the piston, at the last quarter of an inch of movement. In this connection it will be noted that the V groove 105 makes for greater flexibility in adjusting the movement of the door 65
- When it is desired to tension the spring it is merely necessary to insert a tool such as a spanner wrench between the lugs 57 and turn the spring to the desired tension and to locate the hook link 69 behind the proper lug. The hold-open feature is accomplished by means of the pin 109 engaging in the opening 113 in the spring 111, the pin being located in the opening 107, which is opposite the opening 113, when the door is opened 70 the desired extent. When it is desired to close the door it is merely necessary to force the door in a closing direction sufficiently to release the head of the pin from the spring whereby the door check is then free to function in the closing movement as described. 75
- When it is desired to adjust the check to a door of the opposite hand, it is merely necessary to invert the spring on the hub and spindle and lock the end behind the opposite lug 67 on the casing wall. The flexible chain is then wrapped and secured in the opposite direction and the hub 73 is inverted on the end of the main operating spindle. The locking spring 111 is then located on the opposite wall 80 of the casing, the screw 110 being secured in a hole provided on the opposite side. The fluid checking device may be readjusted in one of two ways; first, by removing the screws 49 and reversing the fluid device bodily within the casing; or, second, by adjusting the position of the piston relative to the main spindle in the neutral position at the opposite ends of the cylinder, or, in other words, 85 reversing the checking end without reversing the cylinder bodily. This is possible in the single acting check inasmuch as the two ends are similarly constructed and it will only be necessary to readjust the screws to provide the checking end at the opposite end 90 of the cylinder and to reverse the initial location of the piston in the cylinder. In either case, however, it will be obvious that the parts of the checking device are readily adaptable for installation on doors of either hand by merely reversing the parts and that by this arrangement a much more flexible device is realized. This makes for cheapness in manufacture and simplicity in installation 95 and further permits the reversibility of parts in the various checking devices without the necessity of keeping many types of parts in stock. 100
- The operation of the double check is similar in principle to the single check, with the exception that the piston is provided with a double rack and operates towards the same end of the cylinder in movement of the door on either side of the center line. 105
- Referring to Figure 7, as a matter of illustration, in the event the door is moved counter-clockwise, as seen in plan, the main spindle will likewise be counter-clockwise to cause the winding of the spring 122 while permitting the spring 123 to remain in position. 110

tion shown. During this movement the mutilated gear engages the rack shown on the left-hand side which causes the piston to move away from the checking end. After 5 the door has been moved a predetermined amount, the co-operation of the grooves 161 and 162 effects a back-checking of the door at which point the arm 132 is latched behind the plunger 164 for holding the door in its 10 open position. To close the door it is merely necessary to force it in a closed direction sufficiently to release the spring plunger whereby the wound spring 122 will close the door by moving the main spindle in a clockwise direction. This movement of the main 15 spindle through the instrumentality of the gear and rack causes the piston to approach the checking end of the cylinder whereby the door is checked in the manner desired 20 through the instrumentality of the fluid ports and the adjusting screws and the V groove 163 in the head of the piston. When the door is swung in the clockwise direction from the center line it is understood that the gear will 25 cooperate with the right-hand rack in a manner to impart a similar movement to the piston, but that the spring 123 will be wound and the spring 122 permitted to remain in the position shown. 30 When it is desired to adjust the door to the center line of the sill this may be done by merely adjusting the opposite screws 136 in a manner to cause the door to be accurately centered. It is to be understood in connection 35 with the double acting check as shown in Figure 8, the casing 127 may be mounted in a second casing, as when installed in a concrete floor, and that all of the features for making the casing watertight, shown and described 40 in connection with the single acting check, may likewise be employed. In the event the hold-open feature is not desired, spring pressed plunger 164 in the double acting check may be removed, or the pins 108 in the single acting check may be 45 removed.

Attention is also directed to the fact that the spring mechanism in both devices are interchangeable and are similar, irrespective of 50 the way the spring is wound, it merely being necessary to invert the spring to change its direction of winding.

In mounting the door on hinges independently of the door check, great flexibility is 55 realized in that the lever arrangement between the door and the checking device may be varied by merely shifting the location of the checking device relative to the center line, and also in practical application the device may be located in different positions from side to side of the door opening by means of the slide connection between the checking device and the door, without impairing the operation thereof. This may be 60 found highly desirable in installations where

beams or other obstructions are located in the floor.

When the device is mounted in a wooden floor brackets may be provided on the side of the casing, which are secured to wooden 70 beams beneath the floor level.

One highly desirable advantage is realized in mounting the door on separate hinges whereby in constructing new buildings the doors may be completely mounted before the 75 door checks are installed, it merely being necessary in such cases to supply the hinges and the slides and slide guides which are mounted on the bottom edge of the door. At any later date when the building is nearing 80 completion the door checks may be installed in their completely adjusted condition, the door checks having been completely adjusted at the factory, and they may be positioned relative to the door in any manner desirable. It is only necessary to connect the devices to 85 insert the male projection 37 of the connecting arm 33 in the female socket 30 carried by the slide and adjusting the set screw 32. The checking device mounted in this manner is 90 then ready for operation. In all installations, however, it is desirable to locate the center of the main spindle near the hinge center of the door so that the connecting arm 95 between the check and the door will be maintained for a large part under the door in all positions and out of the main passage-way through the door and in a location where it will be unnoticed.

I claim:

1. A door check comprising a spindle and a fluid checking device operatively connected to said spindle, a second spindle, and a spring mechanism connected to said second spindle to resist rotation thereof in one direction, and means connected to said first spindle and selectively connected to said second spindle at one of a plurality of locations circumferentially disposed relative to said second spindle. 100

2. A door check comprising a pair of spindles each having a hub, a fluid checking device operatively connected with the first of said spindles, and spring means operatively connected with the second of said spindles, the hub of said second spindle having a plurality of lugs thereon; and a flexible element having one end connected to the hub of said first spindle and a means at its opposite end to selectively engage one of said lugs. 105

3. In a door check, a casing, a fluid checking device having a spindle adapted to be connected to a door, in said casing, a second spindle, a spring on said second spindle, having one end anchored to said casing and its other end secured to said second spindle and means comprising a flexible element, and securing means for said flexible element on said second spindle, connecting said fluid checking spindle and second spindle, said means 110

115

120

125

130

selectively connecting said parts in a manner to determine the tension of said spring.

4. A door check comprising a spindle, a fluid checking device operatively connected with said spindle, a second spindle, a spring mounted on said spindle having one end secured thereto and its opposite end stationarily fixed, said second spindle upon rotation determining the tension of said spring, a connecting means attached at one end to said first spindle and means for selectively securing the opposite end of said attaching means to one of a plurality of angularly spaced points of attachment on said second spindle where-
5 by the tension of said spring may be varied by changing the location of attachment between said connecting means and said second spindle.

5. A door check comprising a spindle having a fluid checking device operatively connected thereto, a second spindle having spring means connected thereto to resist rotation thereof in one direction, said second spindle deriving its rotation from said first spindle in said direction, and means for connecting said spindles whereby a uniform angular velocity of said first spindle will impart a negatively accelerated angular velocity to said second spindle.

6. In a device of the character described, the combination of a door and a door check, a guide on said door, a slide means in said guide, an element pivoted to said slide means, an arm connected to said door check and means operable from the lateral direction for detachably connecting said element and arm.

7. A door check comprising a spindle having a fluid checking device connected thereto, a spring means and a stop, a flexible element connected to said spring means and having its opposite end engaged on said stop, an arm on said spindle adapted to engage with said flexible element in one direction of rotation to tension said spring and to dis-
40 engage said flexible element in the opposite direction of rotation, and leave said flexible element on said stop.

8. A door check comprising a spindle having a fluid checking device connected thereto, a spring means and an adjustable stop, a flexible element connected to said spring means and having its opposite end engaged on said stop, an arm on said spindle adapted to engage with said flexible element in one direction of rotation to tension said spring and to disengage said flexible element in the opposite direction of rotation, and leave said flexible element on said adjustable stop.

9. A door check having a spindle, a fluid checking device connected to influence the movement of said spindle, a pair of arms on said spindle, spring means and means for connecting said spring means to each of said arms, stops engaging said connecting means, for determining the neutral position of said

spindle and means for adjusting said stops.

10. A door check having a spindle, a fluid checking device connected thereto, arms on said spindle, a pair of springs oppositely tensioned, and flexible elements connecting one of said springs to one arm and the other of said springs to the other arm, said arms engaging said flexible element in one direction of rotation and being free of said flexible element in the other direction of rotation, stops for said flexible elements determining the neutral position of said spindle and means for adjusting said stops.

11. A double acting door check comprising a spindle, having a pair of arms thereon, a fluid checking device connected to said arms, a releasable holding means located between said arms when said spindle is in neutral position, said holding means being capable of holding either of said arms when moved to engaging position therewith.

12. In a door check, a fluid checking device comprising a cylinder, a spindle, and a double headed piston in said cylinder, the heads of said piston having V grooves therein, the groove in one head cooperating with a port and by-pass in said cylinder, and the V-groove in the other head cooperating with a groove in said cylinder wall.

13. In a door check a fluid checking device comprising a cylinder, a double headed piston therein and a spindle for said piston, a pinion and double rack connecting said piston and spindle, said cylinder having a by-pass and two controlled ports at one end, and a groove at its opposite end, the heads of said piston having V grooves therein cooperating with said ports and cylinder groove respectively, and the head of said piston which cooperates with said ports having a one-way check valve therethrough.

14. In a door check, a casing, a fluid checking device and spring means in said casing, a spindle projecting above the walls of said casing, a cover plate having a flanged opening therethrough closing said casing and surrounding said spindle, packing between said cover plate and casing and a connecting arm on said spindle being constructed to cooperate with said flange to seal said opening.

15. In a door check, a casing, a fluid checking device and spring means in said casing, a spindle projecting above the walls of said casing, a cover plate having a flanged opening therethrough closing said casing and surrounding said spindle, and a connecting arm secured on the projecting end of said spindle constructed to cooperate with said flange to seal said opening.

16. A door check comprising a fluid checking device and a spring means, connected for operation by the movement of a door, said spring means being capable of being bodily reversed in position and constructed to exert a pull in one direction when in one position as

applied to a door of one hand, and to exert a pull in the opposite direction when in the reverse position as applied to a door of the opposite hand.

- 5 17. A door check comprising a spindle having a hub, and a fluid checking device connected for operation with said spindle, spring means and a flexible element connecting said hub and spring means, said hub, spring means and flexible element being bodily reversible in position whereby said spring means may resist rotation of said spindle in one direction when in one position and in the opposite direction when in reverse position.
- 10 18. A door check including in its construction a casing having a pair of spring anchoring means thereon, a spindle having a hub, a reversible spring on said spindle having one end engaging one of said anchoring means in one position and the other of said anchoring means in reverse position and its other end secured to said spindle to exert a torque thereto in opposite directions in reverse positions, said hub having a plurality of lugs thereon, and a flexible connecting element secured at one end to means operatively connected with a fluid checking device, and having a securing means at its opposite end adapted to selectively engage one of said lugs
- 25 19. A door check comprising a casing, a spindle in said casing having a fluid checking device operatively connected thereto, spring means operatively connected to said spindle for rotating said spindle in one direction, a hub on said spindle and a socketed spring on said casing, and means selectively positioned in one of a plurality of receiving means in said hub for cooperation with said socketed spring to yieldingly lock said spindle in opposition to said spring after a selected predetermined angular movement.
- 30 40 45 Signed at Los Angeles, California, this twelfth day of November, 1927.

LEWIS C. NORTON.
